UNITED STATES PATENT OFFICE.

GEORGE F. GRUVER, OF COVINGTON, KENTUCKY.

TRIPARTITE GAME-BOARD.

SPECIFICATION forming part of Letters Patent No. 611,450, dated September 27, 1898.

Application filed March 3, 1898. Serial No. 872,360. (No model.)

To all whom it may concern:

Be it known that I, GEORGE F. GRUVER, a citizen of the United States, and a resident of Covington, Kenton county, State of Kentucky, have invented a certain new and useful Tripartite Game-Board; and I do hereby declare the following to be a clear, full, and exact description of the invention, such as will enable others skilled in the art to which it appertains to make and use the same, attention being called to the accompanying drawing, with the reference-letters marked thereon, which forms a part of this specification.

15 This invention relates to games of the kind where a number of markers or checkers are moved upon a board in accordance with certain established rules. These latter are based upon certain lines, figures, subdivisions, &c., 20 arranged upon the board and govern the moves of the checkers to and from and between the parts mentioned.

25 My invention relates particularly to the game-board and to the provision of certain lines, figures, fields, and subdivisions thereon, the leading feature of which is an arrangement whereby three players are enabled to play at the same time.

30 In the following specification and particularly pointed out in the claims is found a full description of the invention and its manner of use and arrangement, which latter is also illustrated in the accompanying drawing, which shows a plan view of the game-board.

35 The shape of the board is substantially that of a triangle with the corners removed. It contains three sections *a*, one for each player, and a center section *b*, connecting all three sections *a*, and by moving over which one 40 player is enabled to enter either one of the two sections of his opponents. These main sections are again subdivided to form smaller parts, figures, or fields upon which the checkers, one of which is shown at *c*, are placed 45 and between which they are manipulated by being moved from one to the other. By preference sections *a* are subdivided like a checker-board, the alternate squares being colored differently, as indicated in lines, the 50 colors being any suitable combination--as, for instance, gold or silver, or otherwise.

A suitable number of checkers *c* are used--as, for instance, eleven--which are placed on the darker fields of the two outer rows, the outermost or longer one of which is designated by *d* and may be termed the "base-line" of each section. In general the rules of checkers may govern, the general aim of a player being to advance his checkers with as little loss as possible over the center field into 55 either one or the two fields of his adversaries until he reaches the base-line of a section, when he obtains what is termed a "king," which is formed by two superposed checkers and the advantage of which is a greater scope 60 as to moves and power to take away the adversary's checkers. The difficult feature of the game consists of moving through the center section, which can only be entered over a field *e*, which I call "entrance." From here 65 to gain one of the entrances to the opponent's sections he may move to right or left over one of the circular fields *f* or to and over the center field *g*. In place of moving in this manner the advance may be accomplished by 70 jumps--that is, by jumping over an opposing checker in front to an empty field behind, in case there be one, the jumped checker being 75 in such case taken. Thus, for instance, a checker may enter the center section by a 80 jump onto entrance-field *e* or by a jump from either one of the squares in the last row and over entrance-field *e* onto one of the fields *f*, provided such latter be empty and a checker occupies *e*, in which case this latter is confiscated 85 by the one jumping it. For the moves and jumps within the central section I suggest the following rules: A checker may move or jump all over in this section from field to field and also out of it, but in this latter case 90 only in the direction of either one of the adversary's sections and never back to the section from whence it came, unless it be a king. Thus a jump out may be made from one of fields *e*, but not from one of the fields *f*, or 95 vice versa, nor shall the center field *g* be jumped from one of the fields *f*. These rules of course are subject to modifications as may be determined by the players. The board may also be used by only two players, in 100 which case the third and unused section is simply barred to either one. The unused

parts h between the sections a , as well as all spaces between fields in the center section b and the border k , surrounding the whole, may be used in a suitable manner to ornament and embellish the game-board. I do this in this case by using colors, and particularly red, white, and blue, which I arrange alternately, as shown, the blank spaces indicating white, those filled with dotted lines ⁵ red, and the ones filled with broken lines blue.

Having described my invention, I claim as new—

1. A game to be used in connection with ¹⁵ markers having the three sections a, a, a , divided in squares, the section b , which connects

all three sections and contains fields e, f and g all as and for the purpose described.

2. A game to be used in connection with markers having the three sections a, a, a , each ²⁰ subdivided into fields, the spaces h between them, the center section which connects them also subdivided and the border which surrounds the whole, all subdivided spaces, parts and fields of the whole embellished with contrasting colors. ²⁵

In testimony whereof I hereunto affix my signature in presence of two witnesses.

GEORGE F. GRUVER.
